BOTTLE STOPPER

Paul R. Gruber, Waterbury, Conn.

Application October 28, 1946, Serial No. 134,330

Term of patent 7 years

(Cl. D58—10)

To all whom it may concern:

Be it known that I, Paul R. Gruber, a citizen of the United States, residing at Waterbury, in the county of New Haven and State of Connecticut, have invented a new, original, and ornamental Design for a Bottle Stopper, of which the following is a specification, reference being had to the accompanying drawing, forming a part thereof.

Fig. 1 is an elevation of a bottle stopper, showing my new design, and,

Fig. 2 is a top plan view of the same.

I claim:

The ornamental design for a bottle stopper, as shown.

PAUL R. GRUBER.
